DRAPERY CARRIER

Fred H. Werner and James J. Graham, Wallingford, Conn., assignors to H. L. Judd Company, Wallingford, Conn., a corporation of Delaware

Application April 16, 1949, Serial No. 87,946

6 Claims. (Cl. 160—126)

1

Our invention relates to a drapery fixture, and in particular to a traverse-slide carrier of the type which may be operated by draw or pull cords.

In drapery fixtures of the character indicated, particularly where the friction of the slides due to the weight of suspended drapes is rather great compared with the stiffness of the draw cord, it frequently happens that after the drapes are drawn together a relaxation of stress in the draw cords may result in an undesired slight parting of the drapes, in a supposedly closed relation of the drapes. In certain cases, it may be very difficult to draw the drapes completely together, without actually having to stand on a stool and pull the slides together by hand.

It is, accordingly, an object of the invention to provide an improved device of the character indicated.

It is another object to provide an improved slide-type drapery fixture in which a slide may be positively held in a selected position.

It is also an object to provide a two-slide drapery fixture in which the two slides may be latchingingly held in a drawn relative position of said slides.

It is still another object to provide a drapery fixture meeting the above objects and incorporating means effective after latching engagement, whereby tension in the draw or pull means may be relieved as the pull is relaxed in the drawn position, so that there may be a minimum of residual stress on the latch means.

Other objects and various further features of the invention will be pointed out or will occur to those skilled in the art from a reading of the following specification in conjunction with the accompanying drawings. In said drawings, which show, for illustrative purposes only, a preferred form of the invention:

Fig. 1 is a rear view in elevation of a traverse-slide drapery carrier incorporating features of the invention;

Fig. 2 is a top view of the arrangement of Fig. 1; and

Fig. 3 is a view similar to Fig. 2 but showing the slide means in another position.

Briefly stated, our invention contemplates an improved slide-type drapery fixture wherein detent means are provided for holding the slide or slides in a given position, whereby relaxation of stress in the draw or pull means may not have the effect of undesirably dislodging the selected position of the slide or slides. In the form to be described, two slides are movable in opposite directions by means of a pull-cord system, and two-

2

way-action detent means are effective, upon pull-cord actuation, to engage the slides against dislodgment from a given relative position. The position so held may be one in which the drapes positioned by the slides are drawn and in longitudinally overlapping relation, and the detent means may in such case comprise cooperating parts carried by each of the slides. If desired, the relation of the slides may be such that lost motion is permitted after a detent engagement and as the slides are drawn closer together, whereby the lost motion may be utilized to relieve the pull-cord stress after relaxing a pull on the pull cord.

Referring to the drawings, my invention is shown in application to a traverse-slide type of drapery carried in which the rod or track 5 is of C-section and is thus defined by spaced opposed longitudinally extending edges 6—7. The rod 5 may be a single piece, or one or more lengths of C-section rod material may be telescoped in a well-known manner. One or more slides 8—9 may be slidable on the track 5, and in the form shown aligned shoes or other guide members 10 on the slides 8—9 may serve to keep the slides 8—9 on the track.

The entire assembly may be supported as by hanging from end brackets 11—12, and in the form shown these end brackets are attached to blocks 13—14 inserted in the rod 5 at each end. The blocks 13—14 may be suitably formed to accommodate pull-cord sheaves. In the form shown, a pull cord 15 is run over a first sheave 16 in the block 14, along the space within the rod 5, through a loop and locking lug 17 in the slide 8, around a sheave 18 in the block 13, back within the rod 5, through a loop and locking lug 19 in the slide 8, and down over a sheave 20 in the block 14. Thus, with the arrangement shown, it will be clear that by pulling the right-hand end (in the sense of Fig. 1) of the cord 15, the slides 8—9 may be pulled together or drawn, and that, by pulling the left-hand end of the cord 15, the slides 8—9 may be separated. The slides 8—9 may include drapery-supporting parts, and in the form shown a part 21 on the slide 9 may longitudinally overlap a projecting finger part 22 on the slide 8, when the slides are in the drawn position (see Fig. 3).

In accordance with our invention, we provide means for holding a given relative position of the slides 8—9, and in the form shown we have provided such holding means in order to sustain the longitudinally overlapped relation of Fig. 3, which will be a central position in most applications of our carrier. Such holding means

may be effective upon actuation of the pull cord 15 and as the slides near the drawn limit of their relative movement. The holding means may include a detent member 23 carried by one of the slides (9), and detent keeper means 24 may be formed on or carried by the other slide (8). In the form shown, the detent 23 is a suitably bent strip of spring material, which may be supported on the slide 9, as by a weld 25. By forming the detent dimple 23' with like but opposite slopes on either side thereof, the detent action may be two-way; that is, essentially the same resistance to dislodgement may be presented as to making engagement. The keeper means 24 may not only serve the purpose of engagement with the detent member 23, but in striking an abutment portion 26 on the slide 9 the keeper means 24 may determine the drawn limit of relative movement of the slides 8-9, as will be clear. The detent and keeper means 23-24 is preferably in the general plane of alignment of the aligned shoes 10 so that detent action may be substantially uniformly sustained by both edges 6-7 of the track.

As has been suggested above, we prefer that there be some lost relative motion between the slides 8-9 after effecting a detent engagement. Such lost motion may be effectively provided by suitably spacing the detent dimple 23' from the abutment 26 on the slide 9. It will be clear that such lost motion after effecting a detent engagement may usefully provide a means for relieving tension stress in the draw cord 15, so that the detent engagement need not be subjected to residual stress after a drawing pull on the cord 15 has been relaxed.

It will be clear that we have described a simple drapery fixture having the new and useful function of resisting dislodgment from a given selected position. Our improvement is such that it may be applied readily to existing types of traverse-slide fixtures, and we have shown a means for rendering our holding means effective even in the presence of friction and stretch in the pull-cord or drawing mechanism.

While we have described our invention in detail for the preferred form shown, it will be understood that modifications may be made within the scope of the invention as defined in the appended claims.

We claim:

1. In a drapery fixture of the character indicated, a track, two slides slidable on said track, pull means including strings attached to said slides, keeper means on one of said slides, and spring-detent means on the other of said slides and aligned for engagement with said keeper means when said slides are near each other, one of said slides having an elongated recess adjacent the one of said keeper and detent means carried thereby, said slides being movable relatively to each other beyond a drawn engagement of said detent means with said keeper means, so that there may be longitudinal lost motion between said slides after a drawn engagement of said detent means with said keeper means, whereby said lost motion may usefully permit stress relief in said pull means without stressing the engagement of said detent means and said keeper means.

2. A drapery fixture according to claim 1, in which said slides include abutment means deter-

mining the limit of said lost motion after latching.

3. A drapery fixture according to claim 2, in which the abutment means and the keeper means on said one slide are one and the same part.

4. In a drapery fixture of the character indicated, an elongated traverse track, two slides slidable on said track, spring-detent means including separate interengageable members on each of said slides and resiliently relatively deflectable upon engagement of said members, one of said members including two adjacent oppositely inclined cams, the other of said members including follower means for said cams, and drapery-suspension means on said slides and extending on one of said slides in overlapping relation with the detent member carried thereby.

5. In a drapery fixture of the character indicated, an elongated traverse track, two slides slidable on said track, spring-detent means including separate interengageable members on each of said slides and resiliently relatively deflectable upon engagement of said members, said spring-detent means including two cams, one of said cams being carried by one of said members and inclined in a first sloping direction relatively to the longitudinal extent of said track, the other of said cams being carried by one of said members and inclined in a second and generally opposite sloping direction relatively to the longitudinal extent of said track, said members and said cams being so formed that the action of one cam is longitudinally adjacent the action of the other cam, whereby a direct pull of said slides together may suffice to engage said slides and a direct pull of said slides apart may suffice to disengage said slides, and drapery-suspension means on said slides and extending on one of said slides in overlapping relation with the detent member carried thereby.

6. In a drapery fixture of the character indicated, an elongated track, two slides slidable on said track, two-way-action detent means comprising a spring carried by one of said slides and including first latch means at the free end thereof, and second latch means carried by the other of said slides, both said latch means being aligned for interception and mutual engagement upon relative approach of said members, said latch means including two oppositely sloping cams each inclined with respect to the longitudinal extent of said track, said latch means and said cams being so formed that the action of one cam is longitudinally adjacent the action of the other cam, and drapery-suspension means on said slides and extending on one of said slides in overlapping relation with the latch means carried thereby.
